UNITED STATES PATENT OFFICE.

WILLIAM F. DUNCKER, OF STEELTON, PENNSYLVANIA.

TROLLEY.

SPECIFICATION forming part of Letters Patent No. 511,763, dated January 2, 1894.

Application filed August 26, 1893. Serial No. 484,126. (No model.)

To all whom it may concern:

Be it known that I, WILLIAM F. DUNCKER, a citizen of the United States, residing at Steelton, in the county of Dauphin and State 5 of Pennsylvania, have invented a new and useful Trolley, of which the following is a specification.

The invention relates to improvements in trolleys and ice-cleaning attachments.

10 The object of the present invention is to improve the construction of trolleys, and to provide one which, should the wire become displaced from the center groove or pulley, will return the same to the center groove or 15 pulley automatically, and which will prevent any liability of its leaving the wire.

A further object of the invention is to enable the improvements to be readily applied to the ordinary construction of trolley without 20 any material alteration of the same.

The invention also has for its object to provide an ice-cleaning attachment adapted to be readily applied to the trolley and removed therefrom, and capable of effectually crushing 25 the ice on a wire and of removing the crushed ice therefrom and of leaving the wire clean and free of ice for the trolley.

30 The invention consists in the construction and novel combination and arrangement of parts hereinafter fully described, illustrated in the accompanying drawings and pointed out in the claims hereto appended.

In the drawings—Figure 1 is a perspective view of a trolley constructed in accordance 35 with this invention, and provided with an ice cleaning attachment. Fig. 2 is a vertical sectional view of the ice-cleaning attachment. Fig. 3 is a detail perspective view of the rocking or oscillating ice-crusher and cleaner. 40 Fig. 4 is a detail perspective view of the trolley, the ice-cleaning attachment being removed. Fig. 5 is a transverse sectional view of the same. Fig. 6 is a longitudinal sectional view of the trolley.

45 Like numerals of reference indicate corresponding parts in all the figures of the drawings.

1 designates a trolley socket provided at its top with ears 2, between which is journaled 50 a pulley 3 and at the sides of which are journaled outwardly tapering conical bodies 4.

The outwardly extending substantially conical bodies 4 are journaled at opposite sides of the pulley 3, and are provided with spiral grooves 5 inclined inward toward the trolley 55 pulley 3, and adapted, should a wire leave the trolley pulley, to receive and conduct the same back to the trolley pulley, and thereby effectually prevent a trolley from leaving a wire. These grooved bodies or sections are 60 capable of being readily applied to the ordinary construction of trolley, and do not in any manner interfere with the construction of the same or require an alteration thereof; and they are provided at their outer ends or 65 apexes with pivoted disks 6 to form stops to catch the wire to prevent any liability of the trolley moving laterally too far, and becoming disengaged from the wire.

The ice-cleaning attachment consists of a 70 frame 7 adapted to be detachably secured to the trolley socket, and a rocking ice-crusher and cleaner 8, which is journaled between outwardly extending arms 9 of the frame 7.

The rocking ice-crusher and cleaner is provided with front and rear transversely disposed rolls 10 and 11, which are journaled between triangular end pieces 12, and the latter are connected by a transverse bar 13, which is interposed between the front and rear rolls. 80 The front and rear rolls taper from their centers to their ends; the rear one 11 is constructed of gum, rubber or other elastic material, and is corrugated longitudinally; and the front roll 10 is constructed of suitable metal, 85 and is of twice the diameter of the rear roll. By constructing the rear elastic roll 11 of less diameter than the front roll it is caused to drag and partially rotate and operate as a brush to sweep the crushed ice from a wire. 90 This partial rotation and partial dragging of the elastic corrugated roll effectually removes the ice from the wire as fast as the ice is crushed by the front metallic roll.

In order to prevent the ice-cleaning attachment from being broken through contact with some obstruction, and to enable it to readily conform to the position of the trolley the frame is constructed of two sections 14 and 15, which are connected at the rear side of the frame 100 by hinges 16, and are held normally in proper position as illustrated in Fig. 1 of the accompa-

- nying drawings by one or more spiral springs 17. The lower section is provided at its lower edge with an inclined curved groove 18, and has secured to it opposite the groove a detachable clamp 19, which is provided with a recess similar to the groove 18; and the curved groove 18 and the recess of the clamp form an inclined circular opening to receive the trolley socket.
- 10 The ice-cleaning attachment may be readily removed by means of a detachable clamp 19. The ice-cleaning attachment is of the same width of the trolley, and is adapted to conform to the movements of the same, and it is 15 in engagement with a wire whenever the trolley is in contact with the same.
- It will be seen that the trolley and the attachment are simple and comparatively inexpensive in construction, that the trolley is effectively prevented from accidentally leaving a wire, and that the ice-cleaning attachment is capable of readily removing the ice from the wire. It will also be apparent that the improvements in trolleys may be readily applied to the ordinary construction of trolleys without altering the construction of the same, and that the ice-cleaning attachment may be readily applied to and removed from the trolley at pleasure.
- 30 Changes in the form, proportion and the minor details of construction may be resorted to without departing from the principle or sacrificing any of the advantages of this invention.
- 35 What I claim is—
1. The combination of a trolley socket, a pulley mounted therein, separate outwardly tapering bodies journaled at opposite sides to the pulley and provided with spiral grooves,
  - 40 and an ice-cleaning attachment comprising a frame and being of substantially the same width as the trolley and detachably secured to the socket, and a rocking ice-crusher and cleaner journaled on the frame and provided with rolls, substantially as described.
  - 45 2. A trolley having a pulley and provided at opposite sides of the same with separate outwardly tapering conical bodies provided with spiral grooves, substantially as described.
  - 50 3. A trolley having a pulley and provided at opposite sides of the same with outwardly tapering spirally grooved journaled bodies and having disks secured to the outer ends of the same, substantially as described.
  - 55 4. An ice-cleaning attachment for trolleys comprising a frame or support designed to be detachably secured to a trolley, an oscillating frame journaled on the said frame or support 60 and provided with transversely disposed rolls adapted to engage a wire, substantially as described.
  - 65 5. The combination with a trolley having a pulley, of an upwardly extending frame mounted on the trolley and arranged in ad-

vance of the pulley, and a roller journaled on the frame and adapted to engage a wire, substantially as described.

6. The combination with a trolley having a pulley, of an ice-cleaning attachment, comprising a frame or support mounted on the trolley in advance of the pulley thereof, and front and rear rolls tapering from their centers to their ends and arranged parallel with each other and adapted to engage a wire, substantially as described.

7. The combination with a trolley having a pulley, of an ice-cleaning attachment comprising a frame or support mounted on the trolley in advance of the pulley thereof, and a pair of parallel rolls of different diameters journaled transversely of the frame or support and adapted to engage a wire, substantially as described.

8. An ice-cleaning attachment comprising 85 a frame or support and a pair of rolls journaled on the frame or support and tapering from their centers to their ends and being of different diameters, the rear roll being the smaller, substantially as described.

9. An ice-cleaning attachment for trolleys comprising a frame or support and a pair of transversely disposed rolls of different diameters, the front one being constructed of metal, and the rear one being constructed of 95 elastic material, substantially as described.

10. An ice-cleaning attachment for trolleys comprising a frame or support, and the transversely disposed rolls of different diameters, the rear roll being the smaller and constructed 100 of elastic material and being corrugated substantially as described.

11. The combination with a trolley having a pulley, of an ice-cleaning attachment comprising a main frame or support mounted on 105 the trolley in advance of the pulley and provided with outwardly extending arms, a rocking frame journaled between the arms, and rolls mounted on the rocking frame and adapted to engage a wire, substantially as 110 described.

12. An attachment for trolleys comprising a main frame or support provided with outwardly extending arms, an oscillating frame having end pieces pivoted to said arms and 115 provided with a connecting bar secured to the end pieces, and rolls arranged on opposite sides of the connecting piece and journaled on the end pieces, substantially as described.

13. An ice-cleaning attachment for trolleys comprising a main frame composed of upper and lower sections hinged together, the lower section being provided with means for detachably securing it to a trolley, a spring for holding the sections in operative position, and 120 rolls carried by the outer section, substantially as described.

14. An ice-cleaning attachment for trolleys comprising a main frame or support having upper and lower sections hinged at their rear 125 130

faces, the upper section being provided with arms, a spring for holding the sections of the main frame or support in operative position, an oscillating or rocking frame journaled between said arms, and rolls carried by the oscillating or rocking frame, substantially as described.

In testimony that I claim the foregoing as my own I have hereto affixed my signature in the presence of two witnesses.

WILLIAM F. DUNCKER.
